UNITED STATES PATENT OFFICE.

CHARLES F. COOK, OF HOUSTON, TEXAS, ASSIGNOR OF ONE-HALF TO J. E. WALTON, OF HOUSTON, TEXAS.

STOVE.

1,255,295.

Specification of Letters Patent.

Patented Feb. 5, 1918.

Application filed January 11, 1917. Serial No. 141,774.

To all whom it may concern:

Be it known that I, CHARLES F. COOK, a citizen of the United States, residing at Houston, in the county of Harris and State 5 of Texas, have invented certain new and useful Improvements in Stoves, of which the following is a specification.

This invention relates to new and useful improvements in stoves.

10 The object of the invention is to provide a stove of the character described which is provided with a novel form of combustion chamber and equipped with an oil burner which is contained in said chamber and 15 adapted to utilize oil as a fuel. The form of stove shown is designed for heating purposes only although the stove may also be designed for cooking purposes if desired.

With the above and other objects in view 20 the invention has particular relation to certain novel features of construction, arrangement of parts and use, an example of which is given in this specification and illustrated in the accompanying drawings wherein:

25 Figure 1 is a vertical sectional view of the stove.

Fig. 2 shows a horizontal sectional view taken on the line 2--2 of Fig. 1, and

30 Fig. 3 is a transverse sectional view of the burner taken on the line 3--3 of Fig. 1.

Referring now more particularly to the drawings wherein like numerals of reference designate similar parts in each of the figures, the numeral 1 refers to the body or 35 outer shell of the stove which is composed usually of sheet metal and may be formed into any particular design desired; the numeral 2 indicates the combustion chamber formed by the upper and lower transverse 40 partitions 3 and 4 respectively, and the front wall 5. These transverse partitions extend from one side of the stove to the other, are arranged parallel and spaced a sufficient distance apart to form the combustion chamber 45 and also extend from the rear wall of the stove forwardly, and are bolted or otherwise secured at their margins to the corresponding side walls and rear wall of the stove body 1. The vertical partition extends from 50 side to side of the stove and is secured at its upper and lower margins, respectively, to the corresponding partitions 3 and 4. The front wall of the stove is provided with a circular opening which is normally closed 55 by the circular door 6 having the inwardly

projecting annular flange 7 which fits closely within the door opening. The front wall 5 of the combustion chamber has also a circular opening normally closed by the door 8 having the annular inwardly projecting 60 flange 9 which fits closely within said opening. The door 8 has an air inlet 10 which extends out through a central opening in the door 6 and which is closely surrounded by the sleeve 11 integral with and projecting inwardly from said last mentioned door and the passage of air through this inlet into the combustion chamber is controlled by means of the ventilator 12 of any well known form. 70

Supported by the partition 4, within the combustion chamber is the pan 12 which is preferably lined with asbestos, and alined over which is the burner nozzle 13. A fuel tank 14 is fixed above the stove and leading from it is the fuel pipe 15 which is controlled by the cut-off valve 16 by means of which the flow of fuel through the pipe may be regulated or entirely cut off. This pipe 15 enters the stove through the side of the 80 shell, passing transversely through the combustion chamber and is formed into a burner consisting of the parallel sections 17, 17', the free end of the latter of which is turned downwardly and formed into the nozzle 13 85 extending underneath and parallel to the said sections 17, 17', said nozzle being provided with discharge outlets 18, 18, to permit the escape of the fuel therefrom. The burner supports suitable gas targets 19, 19, 90 which are arcuate in cross section and are arranged above the discharge openings 18 so as to deflect the blaze and protect the upper partition 3 and distribute the heat throughout the combustion chamber. A 95 primer pipe 20 is fixed to the partition 3 and extends up through the top of the stove and its upper end is closed by means of the door 21. When it is desired to start a fire, a quantity of fuel such as crude oil or kerosene is poured through the primer pipe 20 and caught by the pan 12. This fuel is then ignited and the valve 16 opened to admit fuel from the tank 14. The fire from the pan will ignite the fuel which is discharged 100 from the pipe 15 through the discharge outlets 18 and the blaze therefrom will be deflected from the gas targets 19, 19. At the same time, the burner sections 17, 17' will be heated by the blaze and the fuel therein 105 110

converted into gas which will thereafter escape through the discharge outlets 18, 18, and be ignited in the combustion chamber as discharged. The desired quantity of air 5 is admitted by adjusting the ventilator 12 and passes through the air inlet 10 into the combustion chamber and thence through the flue opening 22, provided in the rear part of the partition 4 and thence forwardly under and up in front of the combustion chamber and then passes out through the stove pipe 23. The heated air will thus be distributed all around the walls of the stove causing the stove to radiate heat uniformly 10 from all sides.

A needle valve 16' is provided to regulate the flow of fuel to the burner, the cut off valve 16 being utilized chiefly to entirely cut off the fuel when the stove is not in use.

20 What I claim is:

1. A sheet metal stove comprising top and bottom and front and rear walls, a combustion chamber within said stove comprising a top and bottom wall and a front wall, the 25 walls of said combustion chamber extending from side to side of said stove and spaced respectively from the front and top and bottom walls thereof, a flue in the top wall of the stove at the rear thereof, a transverse 30 air inlet extending through the front walls of the stove and combustion chamber, a burner in said combustion chamber arranged in the path of air entering said inlet,

and an air outlet in the bottom wall of the combustion chamber at the rear thereof 35 whereby air entering said inlet flows across said burner and out said outlet and around the exterior of the combustion chamber.

2. A sheet metal stove comprising top and bottom and front and rear walls, a combustion chamber within said stove comprising a top and bottom wall and a front wall, the walls of said combustion chamber extending from side to side of said stove and spaced 40 respectively from the front and top and bottom walls thereof, a flue in the top wall of the stove at the rear thereof, a transverse air inlet extending through the front walls of the stove and combustion chamber, a burner in said combustion chamber comprising a drip pan, a nozzle above said pan and deflector plates above said nozzle arranged 45 in the path of air entering said inlet, and an air outlet in the bottom wall of the combustion chamber at the rear thereof whereby 50 air entering said inlet flows across said burner and out said outlet and around the exterior of the combustion chamber.

In testimony whereof I have signed my name to this specification in the presence of 55 two subscribing witnesses.

CHARLES F. COOK.
